Primary Examiner — Susan Bennett Hattan*Assistant Examiner* — Barbara Lohr(74) *Attorney, Agent, or Firm* — Williams Mullen(57) **CLAIM**

We claim the ornamental design for a wicker yarn, as shown and described.

DESCRIPTION

FIG. 1 is a right side view of a wicker yarn of the present invention;

FIG. 2 is a top view of a wicker yarn of the present invention;

FIG. 3 is a left side view of a wicker yarn of the present invention;

FIG. 4 is a bottom view of a wicker yarn of the present invention;

FIG. 5 is a cross sectional view of a wicker yarn as viewed from FIG. 4, section 5—5 of the present invention; and, FIG. 6 is a perspective view of a wicker yarn of the present invention.

The design is shown broken away and bracketed in FIGS. 1-4, 6 in order to show that a specific length of wicker yarn forms no part of the claimed design.

Any broken lines are intended for the purpose of illustration only and form no part of the claimed design.
